(57) **CLAIM**

The ornamental design for a media player device as shown and described.

DESCRIPTION

FIG. 1 is a front elevation view of a media player device, according to a first embodiment of the invention.

FIG. 2 is rear elevation view of the first embodiment.

FIG. 3 is a left side view of the first embodiment.

FIG. 4 is a right side view of the first embodiment.

FIG. 5 is a top plan view of the first embodiment.

FIG. 6 is a bottom plan view of the first embodiment.

FIG. 7 is a perspective view of the first embodiment.

FIG. 8 is a second perspective view of the first embodiment.

FIG. 9 is a front elevation view of a media player device, according to a second embodiment of the invention.

FIG. 10 is rear elevation view of the second embodiment.

FIG. 11 is a left side view of the second embodiment.

FIG. 12 is a right side view of the second embodiment.

FIG. 13 is a top plan view of the second embodiment.

FIG. 14 is a bottom plan view of the second embodiment.

FIG. 15 is a perspective view of the second embodiment; and,

FIG. 16 is a second perspective view of the second embodiment.

The features shown in dash-dash broken lines do not form part of the claimed design. The dot-dash broken lines show boundaries in certain embodiments of the claimed design. In some embodiments, the media player device can be a subwoofer speaker.
